COMBINATION TOOTHBRUSH AND TOOTHPASTE HOLDER OR THE LIKE

George L. Wise, 3601 W. Gilbert St.,
Muncie, Ind. 47304

Filed Feb. 9, 1966, Ser. No. 1,061

Term of patent 14 years

(Cl. D4—3)

FIG. 3

FIG. 1 is a perspective view of a combination toothbrush and toothpaste holder or the like showing my new design; and

FIG. 2 is an end view of the holder; and

FIG. 3 is a top view of the holder with the front cover open.

The elements shown in broken lines in FIG. 2 are included for illustrative purposes only.

I claim:

The ornamental design for a combination toothbrush and toothpaste holder or the like, as shown and described.
